APPARATUS FOR FUSION ELECTROLYSIS OF
REACTIVE METALS

Ralph M. Sarla, Ramsey, N.J., and Ernst O. Schneidersmann, Wanne-Eickel, Germany, assignors to Union Carbide Corporation, a corporation of New York

Filed Feb. 20, 1958, Ser. No. 716,322

6 Claims. (Cl. 204—225)

This invention relates to a high-temperature cell for the fusion electrolysis of the high melting point reactive metals of groups IV, V and VI of the periodic table. More specifically, the invention is concerned with a cell for the electrolysis of the halides of such reactive metals in a fused salt bath consisting of alkali or alkaline earth metal halides.

Reactive metals of groups IV, V and VI of the periodic table are prone to embrittlement if contacted with air at the high temperatures at which their fusion electrolysis production is conducted. The inherent susceptibility of these metals to contamination by oxygen and nitrogen, particularly, requires that certain measures be taken to protect these metals when they are still in their pure, newly deposited, form.

The most successful measure instituted to maintain the purity of the deposited reactive metal is to perform the electrolysis under vacuum or under the protective shield of an inert gas. Although this method of present-day practice is entirely successful, removal of the cathode on which the metal is deposited in the fused salt bath is eventually necessary, entailing interruption of the entire process. The reactive metal deposit, once withdrawn, must then be allowed to cool, since its exposure to the atmosphere in its hot condition would quickly negate the purity protection afforded it within the shielding enclosure of the cell. This cooling period, however, is sufficiently long to allow solidification of the salt bath, which must then be remelted for the next operation. A batch-type operation of this nature increases the cost of the metal considerably and represents an extremely inefficient method of production, for the cell is idle almost as long as it is productive.

The high temperatures necessary in the fusion electrolysis of the refractory metal halides, and the readiness of the pure metals to react in the atmosphere have, until now, prevented the development of a continuous or semi-continuous method for removal of the cathode products.

With a view to overcoming such prior art shortcomings, it is an object of this invention to provide an electrolytic cell which is compatible with a practically continuous production of high melting point reactive metals by fusion electrolysis.

A further object of the invention is to provide an electrolytic cell which operates under conditions which exclude air or moisture at elevated temperatures, is simple to control, and is capable of continuously producing reactive metals of high purity.

These and other objects and advantages are achieved by the incorporation in an electrolytic cell of an assembly having a plurality of cathodes which can be shifted from side to side over the cell entrance while maintaining an effective gas tight seal.

Referring now to the attached drawings,

Fig. 1 illustrates, in cross section, the apparatus of the invention.

Fig. 2 is an enlarged sectional side view of the appa-

2

ratus shown in Fig. 1 and indicates other features of the subject electrolytic cell.

Figs. 3 and 4 are side elevational views of the carriage-bearing assembly for raising the upper cell portion.

5 Referring now to the drawings, to show clearly the position of O-ring seals which make possible the continuous exchange cathodes, the lower cell assembly, comprising the cell, is shown from the top in Fig. 1 and the upper assembly, which permits cathode exchange, is 10 shown from the bottom. This assembly consists of a water-cooled gas-tight chamber 1 containing a graphite crucible 2 which serves as the anode. A plate 3 of conducting material may be pressed against the bottom of the crucible 2 to make electrical contact. The crucible 2 is surrounded by a heating system 4 and is insulated from the chamber 1 by refractory material 5. Completely surrounding the entrance to the chamber and extending outward, a table member 6 with a smoothly-finished surface, the under portion of which is contacted and cooled 15 by a layer of water in a jacket 7, comprises the upper portion of the lower cell assembly.

The upper assembly consists of the twin cathode chambers 8a and 8b attached to a carriage 9, which, in operating position, contacts the plane of the surface of table 25 6. An oval O-ring 10 composed of synthetic plastic, such as polyethylene, resistant to cell effluents, encircles the two openings of the cathode chambers 8a and 8b and is depressed by the weight of the upper assembly so as to seal the combined cathode and cell chambers 30 effectively from the atmosphere.

Assuming the position of the apparatus as indicated in Fig. 1, the lower opening of cathode chamber 8a is in vertical alignment with the cell opening, around which a secondary O-ring 11 is secured. This additional seal 35 supplements O-ring 10 in actual operation but has an even more important function in maintaining an independent seal between cathode chambers 8a and 8b when one is opened to the atmosphere for removal of the metal from the deposition cathode tip.

40 The cathode 12a in central alignment with the walls of the chamber 8a can be lowered through the opening in the lid 13 and is assisted in remaining truly vertical by a seal 14 as the cathode tip is submerged in the electrolyte in the crucible 2, thus completing the electrical circuit.

45 Unexpectedly, it was observed that a conical tip cathode was not attacked by gas evolved from the anodic bottom of the cell. For best results it was found that the distance of the tip of the cathode from the bottom of the anodic crucible should be greater than the space 50 between the cathode and the crucible wall. When these clearances are maintained, preferential growth of the deposit on the tip of the cathode and subsequent shorting out of the D.C. circuit between the cathode and the 55 crucible bottom are prevented. The cathode construction is preferably of cold rolled "A" nickel and that portion of the shaft immediately above the conical tip may be protected from cell gas by a simple carbon or graphite sleeve. The cathodes are further preferably 60 protected by air-cooling means as indicated by the arrows at the top of cathode 12a in Fig. 1.

Pictured in Figs. 3 and 4 are the quick-acting clamps and carriage-bearing assembly for raising the upper cell portion. The toggle clamp 15, when depressed, lowers 65 the shaft 16 so that the wheel 17 presses on the table 6 and raises the carriage 9. When the section is thus lifted, the holding lug 17a is also released and the entire assembly may be easily shifted, so that chamber 8b lies in vertical alignment with the cell opening. Clearance 70 between carriage 9 and table 6 is so adjusted that O-rings 11 and 12 are partially compressed even while carriage 9 is in the raised position. A gas-tight seal may thus be

maintained at all times. Release of the clamps 15 compresses the oval O-ring seals 10 and 11, and immediate lowering of cathode 12b allows continuation of the reactive metal deposition. This procedure permits practically continuous electrolysis, since the deposited material on the tip of the cathode 12a now has ample time to cool, and is subsequently removed through the lid 13. The cathode chamber 8a is evacuated and is then ready for reuse as soon as the cathode 12b, which is at that time being employed, requires removal of deposited metal.

As will be noted in both Figs. 1 and 2, the O-rings 10 and 11 are situated in a manner that will prevent conflict with each other when the exchange of cathode chambers is effected. During this movement, when neither chambers 8a or 8b are resting on O-ring 11, both chambers are in evacuated or inert gas-filled condition. An alternate method for providing a workable, positive seal means is to place a sheet of polyethylene or other suitable plastic between the sliding carriage and the table. Such material acts as an infinite number of O-rings and allows the cathode chambers to be sealed in any position.

Another effective method for maintaining a gas-tight seal without the use of an oval-ring is possible. This may be done by providing multiple rings similar to O-ring 11 along the surface of table 6. These rings should be spaced at intervals equal to the distance between chambers 8a and 8b so that the bottom opening of each such chamber will be encircled by such a ring during operation. Any number of rings may be so provided to correspond with any desired number of cathode chambers.

The entire procedure for shifting cathodes takes but a moment and is extremely simple, inexpensive, compatible with maintaining the purity of the metal deposited on the cathode and makes possible a practically continuous operation. The salt bath, or electrolyte, is under constant protection from air and moisture, and the temperature within the cell is always sufficiently high to prevent its solidification, especially during cathode changes.

In preparing for actual operation of the apparatus of the invention, a fused electrolytic salt mixture is fed into the cell. Suitable electrolytes containing alkali metal halides and alkaline earth metal halides, and a chloride of the desired reactive metal are disclosed and claimed in the copending application of R. M. Sarla, Serial No. 512,297, filed May 31, 1955. The upper and lower assemblies are aligned in secure position with the O-rings depressed to exclude the atmosphere. The cathode of the chamber in use is held in readiness to be lowered into the electrolyte. Referring now to Fig. 2, the cell is evacuated through an outlet 18 to approximately 100 microns after which the chamber and cell may be flooded with an inert gas, such as argon, through the inlet 19, or the operation may proceed under pressures below atmospheric. The temperature within the cell is now elevated to melt the salt and when fusion is complete, the refractory metal halide, which may be gas, liquid or solid, is fed in and combined with the fused salt bath through the opening 20 to form the electrolyte. All is now in readiness for submergence of the cathode into the electrolyte for completion of the electrolysis circuit and for deposition of the pure reactive metal on the cathode tip. The halogen gas which is evolved at the anode rises to fill the area above the electrolyte and is either eliminated by suction through the outlet 21 or by cycling the inert gas.

To offset the possibility of corrosive action by the halogen gas at the elevated temperature within the cell, a series of inlets, hollows, and outlets honeycomb the apparatus for circulation of water for cooling various portions of the equipment independently of each other. Fig. 2 illustrates the sections of the apparatus which are so cooled, and these include, progressing from the lower portion to the upper, the anode, shell, under-portion of the table, cathode chamber, cathode chamber lid and the cathode itself. By so cooling the entire assembly, not only

is the corrosive action of the evolved gas negated, but the seals are protected from burning, or even losing their resiliency.

It is to be understood that a number of modifications 5 may be made in the apparatus of the invention without departing from the spirit thereof. For example, the anode and cathode chambers may be of any desired configuration which would assist in the electrolysis and collection of the end metallic product. While the anode chamber 10 as shown is externally heated, it would also be quite feasible to heat said chamber internally, as by heating elements inserted in the crucible.

Subject matter particularly related to the electrolytic mixtures suitable for use in conjunction with the previously described cell is disclosed and claimed in my co-pending application Serial No. 512,297, filed May 31, 1955.

This application is a continuation-in-part of application Serial No. 631,185, filed December 28, 1956, now abandoned, by R. M. Sarla, entitled "Apparatus for Producing Tantalum," and application Serial No. 631,186, filed December 28, 1956, now abandoned, by R. M. Sarla and E. O. Schneidersmann, entitled "Apparatus for Fusion Electrolysis of Reactive Metals."

25 What is claimed is:

1. In an electrolytic cell for the production of high melting point reactive metals of groups IV, V and VI of the periodic table by the deposition thereof from an electrolytic bath, the combination comprising a lower cell 30 assembly consisting of a water-cooled chamber containing a crucible serving as the cell anode, heating means for heating the contents of said crucible, a table member surrounding the opening to said chamber at the upper portion thereof, and extending outwardly therefrom, an upper cell assembly comprising a plurality of water-cooled cathode chambers secured to a base wheeled carriage slidably mounted on said table member to permit successive immersion in electrolyte of deposition cathodes 35 removably mounted therein; sealing means between said assemblies; means for supplying electric current to said anode and cathode; feeding means for introducing an electrolytic charge into said cell; and means for evacuating and for injecting inert gas in said cell and cathode chamber.

40 2. The cell of claim 1 wherein refractory material is provided between said vacuum chamber and crucible for insulation.

3. The cell of claim 1 wherein plastic O-rings encircle 45 the openings of the cathode chambers, and of the vacuum chamber to provide an effective seal against the atmosphere.

4. The cell of claim 1 wherein plastic O-rings encircle 50 the opening of the anode chamber and are intervallicly spaced along said table member to seal each of said cathode chambers.

5. The cell of claim 2 wherein the distance from the tip of said cathode to the bottom of said crucible is greater than the distance from said cathode to the wall of said crucible.

6. In an electrolytic cell for the production of high melting point reactive metals of groups IV, V and VI of the periodic table, said cell having an inlet for receiving a cathode therein, a cell cover assembly to provide for substantially continuous production of metal which 65 comprises a table member fitted to the top of said cell and having an opening to permit the passage of a cathode therethrough into said cell, a base member movably mounted upon said table member, a plurality of chambers adapted to contain cathodes fixedly and sealably mounted on said base member, said chambers having lower outlets therein extending through said base member to permit a said cathode to be lowered into said cell upon moving said base member on said table member to align a said chamber with said cell, annular seal-

ing means fixed to the lower surface of said base member to surround said chamber outlets and to compressibly and continuously contact the upper surface of said table member, said base member and affixed sealing means arranged upon said table member to be movable thereon to permit alternate alignment of said chambers with said cell and alternate employment of cathodes therein while

5 continuously sealing said chambers and said cell from the atmosphere.
